L. H. BURNHAM

ELECTRICAL APPARATUS

Filed March 23, 1922

Inventor:
Locke H. Burnham,
by *Allard, Dan*
His Attorney.

UNITED STATES PATENT OFFICE.

LOCKE H. BURNHAM, OF PITTSFIELD, MASSACHUSETTS, ASSIGNOR TO GENERAL ELECTRIC COMPANY, A CORPORATION OF NEW YORK.

ELECTRICAL APPARATUS.

Application filed March 23, 1922. Serial No. 546,120.

My invention relates to electrical apparatus which is cooled by being immersed in a body of suitable liquid such as oil. The general object of the invention is to provide an improved arrangement to care for expansion and contraction of the liquid under various conditions which may arise during the operation of the immersed apparatus.

10 It is customary to enclose electrical induction apparatus, such as a transformer, in a casing which is connected with an expansion chamber, the casing and expansion chamber being filled with cooling liquid to a level above the opening of the connector into the expansion chamber. This liquid may expand and contract slowly under the influence of varying temperatures to which it is subjected during normal operation of 15 the apparatus and it may occasionally expand suddenly by reason, for instance, of the sudden generation of considerable volumes of gas resulting from accidental short circuits or arcs in the apparatus. It is desirable that the normally slow and gradual expansion and contraction of the liquid be cared for by permitting a correspondingly slow exchange of liquid back and forth between the casing and the expansion chamber, 20 the rate of exchange being sufficiently retarded or restricted to prevent heated liquid being carried by convection currents from the casing to the expansion chamber. This minimizes contamination of the liquid as it 25 is more easily oxidized by air in the expansion chamber when heated than when cool. In the event, however, of sudden expansion of the liquid, within the casing, it is desirable that quick relief be provided in 30 order to avoid the occurrence of excessive and dangerous pressures within the casing. It is an object of this invention to provide a construction wherein these various desirable results may be attained. Other objects 35 and advantages will appear.

One embodiment of the invention is illustrated in the accompanying drawing which shows a transformer casing connected with an expansion chamber or conservator in accordance with the principles which have been outlined.

In this particular embodiment of the invention, a transformer casing 1 is connected, preferably from its upper portion, by a large pipe 2 with an expansion chamber or

conservator 3. A valve 4 normally closes the opening or passageway through the pipe 2 except for a small opening or passage 5 connecting the contents of this pipe at opposite sides of the valve, this opening 5 being shown here as a small hole through the valve itself. The valve is free to open toward the expansion chamber 3. The casing 1, pipe 2 and expansion chamber 3 are filled with oil or other cooling liquid to a level in the expansion chamber above the upper end of the pipe 2, this level being indicated by the broken lines 6. As the liquid in the casing 1 expands and contracts under the influence of varying temperature, 70 it is permitted to flow to and from the expansion chamber 3 through the opening 5 which, however, is small enough to prevent convection currents. The liquid in contact with the air in the expansion chamber, 75 therefore, remains cool at all times so that it is substantially free from the effects of oxidation. A breather 7 permits air to pass into and out of the expansion chamber 3 as the level 6 of the liquid falls and rises. 80 The pipe 2 preferably extends a little above the bottom of the expansion chamber 3 so that any moisture that may settle in the liquid in this chamber cannot run down into the casing 1 but will collect in a trap 8 85 whence it may be drawn off at intervals.

Upon the occurrence of an accidental fault such as a short circuit or arc in the transformer, a large volume of gas may be suddenly generated and create pressure 90 within the casing 1. The pressure is instantly relieved and prevented from rising to excessive and dangerous values, however, by the large pipe 2, liquid and gas passing quickly into the expansion chamber 3 95 through this large pipe and past the valve 5 which yields to the increased pressure of the liquid and is thereby readily opened toward the expansion chamber. The resulting pressure in the expansion chamber is 100 limited to safe values by rupture of a relief diaphragm 9 which normally closes a large outlet 10 from the expansion chamber.

A construction involving the features disclosed by this invention provides ready relief for pressures occurring in the casing of electrical apparatus immersed in a cooling liquid and danger from excessive pressures is eliminated. At the same time, the apparatus is permitted to function under nor- 110

mal conditions of operation in such manner that the liquid may expand and contract under the influence of varying temperature without contact with air and consequent 5 contamination.

What I claim as new and desire to secure by Letters Patent of the United States, is:—

1. The combination with a casing for electrical apparatus, of an expansion chamber 10 provided with an outlet, there being a passageway connecting said casing and expansion chamber, cooling liquid within the casing and extending through said passageway into the expansion chamber, means responsive to pressure within the casing for varying the effective size of said passageway, and means normally closing said outlet from the expansion chamber and responsive to pressure within said chamber to open 15 said outlet.

2. The combination with a casing for electrical apparatus, of an expansion chamber, there being a passageway connecting said casing and expansion chamber, cooling liquid 20 within the casing and extending through said passageway into the expansion chamber, and a valve for limiting thermal circulation of liquid through said passageway, said valve being arranged to be opened by 25

sudden pressure within the casing and having an opening therethrough smaller than the passageway between the casing and expansion chamber, whereby said smaller opening permits interchange of cooling liquid between said casing and said expansion chamber due to expansion and contraction of the liquid within the casing. 30

3. The combination with a casing for electrical apparatus, of an expansion chamber, there being a passageway connecting 35 said casing and expansion chamber, cooling liquid within the casing and extending through said passageway into the expansion chamber, and a valve for limiting thermal circulation of liquid through said passageway, said valve being arranged to be opened by 40 sudden pressure within the casing, there being an opening connecting the portions of said liquid at opposite sides of the valve 45 smaller than the passageway between the casing and expansion chamber to permit interchange of cooling liquid between said casing and said expansion chamber due to expansion and contraction of the liquid within the casing. 50

In witness whereof, I have hereunto set my hand this 20th day of March, 1922.

LOCKE H. BURNHAM. 55
